UNITED STATES PATENT OFFICE.

CHARLES HAMILTON PAJEAU, OF EVANSTON, ILLINOIS.

DESIGN FOR A TOY RATTLE.

55,880.

Specification for Design.

Patented July 20, 1920.

Application filed April 9, 1920. Serial No. 372,678. Term of patent 7 years.

To all whom it may concern:

Be it known that I, CHARLES HAMILTON PAJEAU, a citizen of the United States, residing at Evanston, in the county of Cook and State of Illinois, have invented a new, original, and ornamental Design for a Toy Rattle, of which the following is a specification, reference being had to the accompanying drawing, forming part thereof.

The figure is an elevation of a toy rattle, showing my new design.

I claim:

The ornamental design for a toy rattle, as shown.

CHARLES HAMILTON PAJEAU.
